PISTON AND CRANKSHAFT CONNECTING
MEANS FOR INTERNAL-COMBUSTION
ENGINES

Robert A. Poage, Ralls County, Mo.

Application October 8, 1945, Serial No. 621,130

4 Claims. (Cl. 74—50)

1

This present invention relates to Diesel engines which complete their cycle in two piston strokes. One of the objects of the invention is the design of an internal combustion engine including cylinders disposed on both sides of the crank shaft and pistons secured to one another and therefore moving in unison. Both pistons are stopped and started by a cushion of air that requires compressing every time the pistons require stopping and starting. In the conventional connecting-rod engine the high piston velocity which is desirable as it gives distance in a short time, reaches a critical value which becomes the source of loss of power due to the mechanical stresses involved in stopping and starting the pistons. The stopping and starting of the pistons is done by the crankshaft and accounts for a loss of 50% in the two-stroke cycle and 75% in the four-stroke cycle engine.

Near the completion of a compression stroke the air pressure rises rapidly and my pistons decelerate at an increasing rate at this time, thereby closely matching piston deceleration to force available to cause same.

Another object of the invention is the provision of an engine the pistons of which are operated in pairs and the crank shaft of which is short and rigid. The crank webs are each formed into a flywheel accommodating a removable crank pin and roller and counter balanced. The crank pin is keyed and locked in the crank webs and together with a crosstie makes the crank construction sturdy. Furthermore the web crosstie acts as an emergency piston stop in the event of loss of compression.

Another and primary object of the invention is the construction of an engine the pistons of which hesitate at both the top and bottom of stroke. The duration of the hesitation is to be determined by the designer. The main purpose is to obtain a higher rate of acceleration and deceleration near the beginning and end of a stroke. This is accomplished by permitting the crank arm to get well past the center line of cylinder bore before the piston gives way from the top and after the piston at the bottom ends its stroke. Thus higher acceleration from the top is obtained while the combustion pressure is highest, furthermore, the entire stroke consumes less time and crank shaft rotation. This results in more power.

The injection should be so timed as to obtain "flame spread" simultaneous with the piston giving way from the top. The more rapidly the piston gives way at this time, the shorter is the

2

time during which the cylinder walls are exposed to the extremely high temperatures of the flames. Heat thus saved early in the stroke will give greater pressure throughout the stroke.

5 ... The scavenging ports, uncovered by the pistons at the bottom of their strokes, are opened quickly to the fullest extent and remain open during the hesitation of the pistons. This permits improved scavenging with shallower ports that use up a lesser fraction of the power stroke as the exhaust valves may be opened later in the power stroke.

Piston hesitation at the top of the stroke gives a stabilized, high compression temperature prior 15 to the injection of fuel; thus the ignition delay period is shortened, the accumulation of fuel reduced, detonation prevented and the proper timing of the injection at various speeds is simplified.

20 With these and other objects in view the invention resides in the novelty of construction, combination and arrangement of parts which will be hereinafter specifically described and claimed in the appended claims.

25 For a full understanding of the invention reference is had to the accompanying drawings in which:

Figure 1 is a central longitudinal section of the intermediate part of the engine, the blower, injection pump and cylinder heads being shown in side view;

Figure 2 is a horizontal section of some parts, other parts being shown in plan view;

30 Figure 3 is a vertical detail section, showing the parts in their position at the beginning of the power stroke;

Figure 4 is a vertical detail section, showing the parts in mid-stroke position;

Figure 5 is a detail side elevation of the crank;

Figure 6 is a plan view of the crank shaft;

Figure 7 is a vertical detail section on line 7—7 of Fig. 2;

Figure 8 is a view of the inner side of a section of the track member.

45 In the drawing in which like characters of reference designate like or similar parts, numeral 2 denotes each of four flat feet which are fastened to a floor or other foundation by bolts 3 and support each a web-like vertical frame portion 4. From the lateral edges of the flat bottom 5 of a crank case 6 extend upwardly and outwardly side walls 7 each integral with or connected to a pair of the frame portions. The upper ends of the walls 7 merge into vertical side walls 8 each of which has a relatively large cir-

cular opening registering with the other opening (Figs. 1, 2). In each opening is inserted the inner end portion 9 of a cylinder 10 the axis of which is horizontally disposed. At the line dividing the end portion from the remaining cylinder section a circumferential flange 11 extends laterally from the cylinder and parallel to the vertical side wall of the crank case. Bolts 12 secure the flange and cylinder to the vertical side walls of the crank case. The section of each cylinder outwardly of the flange consists of an inner and outer shell providing an annular space 13 in which cooling water can circulate and connected on its lower side and near the flange to an inlet pipe 14 and on its upper side and near the outer end of the cylinder head 15 to an outlet pipe 16.

On the front side of either cylinder head is an air cell retainer 17 and the outermost end portion of each cylinder head is formed by a valve cover 18 which contains a conventional rocker arm assembly 19 operated by a valve rod to be described.

The forward end of the valve cover is connected to a tube 21 extending forwardly and inwardly and connected at the inner end to a housing 23 which is attached by bolts 24 to the front wall 25 of the crank case. Through either tube extends a valve push rod 26, the inner and forward end of which is formed into a ball 21. The same is received in a spherical socket formed in the outer end of a cylindrical cam follower 28 which is slidably disposed in a cylindrical hollow in the housing and the headed inner end of which bears against one curved side of a cylindrical cam disc 30. The same is eccentrically mounted upon a cam shaft 31 which is journaled in an opening in the front wall 32 of the housing and surrounded by a packing 33 in the inner enlarged portion of the opening. The rear end of the cam shaft is secured to or integral with the central portion of the crank shaft gear 34 which drives the blower 36, the injection pump 38 and oil pump (not shown) and other movable parts when properly connected.

The blower is connected on either side to a pipe 40 which is connected at the other end to a post 41 communicating with the cylinder and uncovered by the piston still to be described when the same is in the position of the right-hand piston of Figs. 1, 2.

The injection pump 38 is connected by a pipe 43 to an injector 44 (Fig. 2).

The crank shaft gear described is secured to the front end of the crank shaft 45 the aligned portions of which are journaled in bearings 47. Each bearing is mounted in an aperture formed in the outwardly and inwardly enlarged central portion 48 of the front wall or rear wall 25 of the crankcase. Each bearing is provided on its inner side with an oil groove 51. The oil groove of the front bearing of the crank shaft communicates with the forward end of an oil conduit 52 which extends through the front cylindrical portion, the crank portion of the shaft, through one half of the crank pin still to be described, and then radially through the crank pin to roller bearings still to be described. An annular housing 54 surrounds the portion of the crank shaft projecting beyond the rear wall of the crankcase and is attached to such rear wall by bolts 56 and retains a packing 57.

The inner ends of the cylindrical aligned portions of the crank shaft are each integral with the counterbalanced web-like wheel 60 of cast steel. Each wheel is provided with an eccentric

split opening 62 in which one end of a crank pin 63 is held by a key 64. These openings are located diametrically opposite to the weighted portion 66 of the wheel and communicate each with a narrow radial slot 67 which may be narrowed by tightening a bolt 69. The crank pin is surrounded by a hollow ring 70 containing pairs of conical rollers 72 which are lubricated by oil conducted by the oil conduit 52 described (Fig. 2). Each pair of rollers are so arranged that the smaller ends are adjacent to one another. Inwardly of the crank pin and roller bearing is a web cross-tie 74 of heart-shaped cross section which connects the web-like wheels. This cross-tie has a fragmentary cylindrical surface concentric to the longitudinal axis of the crank pin and a pair of intersecting convex surfaces 76 and acts as an emergency piston stop in the event of loss of compression.

The roller bearing ring rotates within a track member 78 which defines an opening and comprises two symmetrical halves bolted together by bolts 79. The same are inserted in holes 80 (Fig. 8). Each half consists of a flange 81 extending laterally of the track opening and provided at the upper and lower ends with parallel abutting portions through which the bolts extend. The opening is bounded at the top and bottom by a semi-cylindrical surface 82 either of which merges at the lower or upper ends into relatively short flat surfaces 83. The same terminate abruptly at their upper or lower ends and form a blunt corner with the ends of a pair of opposed shallow concave surfaces 84 (Figs. 1, 3, 4).

The roller bearing engaging flange of either half of the track member is connected at its outer side by a web 85 to a piston 86 and reinforced by an intermediate vertically disposed flange 87. Each piston has rings 88 near its outer end.

The preceding description applies to both halves of the symmetrical engine structure.

Figure 3 shows the left hand piston in the position at the beginning of the power stroke. The crank roller ring contacts the upper end of the left-hand shallow concave portion 84 and is about to engage the left-hand lower flat surface 83. The crank arm is well past the center line of the cylinder bore and the hesitation of the piston has ended. At the end of the impending stroke the crank arm will occupy a position diametrically opposite of that shown in Fig. 3.

Figure 4 shows the parts in the position of the midstroke.

It will be understood that the details of construction may be varied without departing from the spirit or scope of the invention as defined in the appended claims.

What I claim and desire to protect by Letters Patent is:

1. A piston and crank shaft connecting means for an internal combustion engine, comprising an elongated yoke adapted to be connected to the adjacent ends of two opposed reciprocating pistons and forming a rigid connection therebetween, said yoke being disposed with its longitudinal axis substantially at a right angle to the axis of the pistons and having an elongated opening extending lengthwise thereof and bound by complementary, substantially semi-circular end surfaces, complementary elongated, internally concave intermediate surfaces and complementary opposed substantially flat surfaces between said end surfaces and said intermediate surfaces, a shaft having a portion extending through and

movable in the yoke opening at a right angle to the axis of the pistons, a pair of disks fixed to the shaft in spaced parallel relationship and disposed one on each side of the yoke, and a crank pin extending between the disks and connected thereto eccentrically of the shaft, said crank pin extending through the yoke opening and being disposed for movement therein to engage each of said yoke surfaces during each revolution of the shaft, the shaft portion disposed between the disks being recessed to provide an outer concave portion disposed adjacent the crank pin and an inner portion terminating adjacent the axis of the shaft and defined by corresponding convex inwardly merging portions, said shaft portion being in radial alignment with the crank pin to provide a piston stop.

2. A piston and crank shaft connecting means as in claim 1, the distance between the inner edge of said shaft portion and the outer part of the crank pin being only slightly less than the width of the widest, intermediate part of the yoke opening.

3. A piston and crank shaft connecting means as in claim 1, said disks being counter-balanced with respect to the crank pin to form a flywheel.

4. A piston and crank shaft connecting means as in claim 1, said yoke being formed of detach-

ably connected corresponding symmetrical halves each adapted to be formed integral with one of the pistons.
